UNITED STATES PATENT OFFICE.

WILLIAM M. LITTLE AND JESSIE L. SHERMAN, OF NORPHLET, ARKANSAS.

OIL-SEPARATING APPARATUS.

Application filed December 5, 1925. Serial No. 73,493.

The present invention relates to a separating apparatus for crude oil, and aims to provide means for efficiently and thoroughly separating the water, gas, composition of mud, and like other foreign constituents of crude oil from the good oil.

Another very important object of the invention is to provide in a separating apparatus of this nature, a heating apparatus so that the separator will be adaptable to any climate, under any circumstances, and will separate any gravity or quality of oil.

A specific object of the invention is to provide an improved heating apparatus wherein the same is provided with a perforated feed pipe in the bottom of a boiler structure through which the oil is forced about the flues of the boiler structure and providing a perforated crown sheet over the flues through which the oil is also forced so as to break up the globules and to assist in the separating of the last part of the water from the oil.

Another very important object of the invention is to provide a heating apparatus in combination with a chemical treating equipment for treating the oil after it has passed from the heater and finally a separator for thoroughly eliminating any gas or water which may remain in the oil before it is sent to storage.

Another very important object of the invention is the provision of an apparatus of this nature which is exceedingly simple in all its features, in its details of construction and in its arrangement.

A still further object of the invention is to provide an apparatus of this nature which is thoroughly efficient in its operation, reliable, inexpensive to manufacture and operate, easy to manipulate, one which requires little attention, one which is not likely to readily become out of order, and one which is otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:—

Figure 1 is a top plan view of the appara-

tus embodying the features of our invention. 55

Figure 2 is a vertical longitudinal section through the heating apparatus.

Figure 3 is a sectional elevation of the separator,

Figure 4 is an end elevation of the apparatus,

Figure 5 is a fragmentary section through the chemical treating apparatus, and

Figure 6 is a transverse vertical section taken substantially on the line 6—6 of Figure 1 through the heating apparatus. 65

Referring to the drawings in detail it will be seen that the letter A designates generally the heating apparatus, the letter B the chemical treating apparatus, and the letter C the separator. These units A, B, and C are connected in the order mentioned, the heating apparatus lying in spaced parallel relation with the separator C and the chemical treating apparatus B being disposed 70 transversely therebetween. This assemblage is very compact, but, of course, it may be varied to suit circumstances, and does not form an essential part of our invention.

Referring now in detail to the heating apparatus which is illustrated to particular advantage in Figures 2 and 6 it will be seen that D represents the flow line from the well or other suitable source of crude oil. The crude oil flowing through this pipe line D 85 usually consists of oil, water, gas, and a composition of mud, etc. termed in the art B. S. A branch 5 leads upwardly from the pipe line D and has a valve 6 therein and a branch 7 continues from the pipe line D 90 and has a valve 8 therein. The valve 6 is closed, and the valve 8 is opened when the oil is to be forced through the heating apparatus A, as will become more apparent as the description proceeds. The valve 8 95 is closed, and the valve 6 is opened when it is not necessary or desirable to force the oil through the heater, and the latter is turned off. This is desirable when the oil is thin and the weather exceedingly warm. The 100 heating apparatus is housed within a boiler-like casing 9 of substantial cylindrical formation having the lower portion of one end thereof formed to provide a fire box or chamber 10, in which is mounted a gas burner, or any other suitable source of heat indicated at 11. 105

The gas line is shown at 12, and is con-

trolled by a suitable valve 13. The walls 14 and 15 separate the fire compartment 10 from the rest of the interior of the boiler-like casing 9. A perforated crown sheet 16 extends throughout the length and breadth of the interior of the boiler-like casing 9 coplanar with the wall 15, that is, about equidistant from the top and bottom of the casing. A plurality of flues 17 pierce the wall 14 and the bottom portion of the end wall 18. As is shown to advantage in Figure 6, these flues are gathered in two spaced groups, one to each side of the casing. A perforated closed ended tube 19 lies in the bottom of the casing 9 between the groups of flues 17, and communicates at its ends adjacent wall 14 with the branch 7. In actual practice we find it desirable to construct the apertures of the tube 19 about one-half inch in diameter and to dispose the tube about three inches from the bottom of the boiler. The oil from the branch 7 flows into the tube 19 and enters the boiler-like casing from said tube, the apertures in the tube tending to break the oil, water, gas, and B. S. to make the same separable. The crown sheet is thoroughly welded in the casing 9, and the apertures therein function to the same end as the apertures in the tube 19, as the crude oil is forced therethrough, but are even more effective since the crude oil has been heated by passing through the spaces between the flues 17. A visual level indicating gage 20 is provided one end of the casing 9. On top of the casing 9 there are provided domes 21 and 22. The dome 21 has the branch 5 leading thereto and a break gate 23 is situated within the dome 21 at the point of communication thereof with the branch 5 and serves to break up the crude oil particularly for the purpose of separating the gas globules which are so common in crude oil, thereby making the oil easier to separate and throwing the waste gas, which is of no service, off at pipe 24.

The dome 22 is provided with a screw cap 25 affording ready access to the interior thereof. A standard 26 has its lower end bifurcated to straddle the tube 19 and rest on the bottom of the casing 9. This standard rises between the groups of flues 17 as is indicated to advantage in Figure 6. A rocker 27 is pivoted intermediate its ends on the upper end of the standard 26 as is indicated at 28. Another rocker 29 is pivoted intermediate its ends to the standard 26 immediately above the lower bifurcated end thereof as is indicated at 30. A link 31 connects adjacent ends of the rockers 27 and 29. The other end of the rocker 27 is pivotally engaged as at 32 with a float 33. This float 33 is in the form of a hollow container having a screw cap 34 at the top end thereof. By removing the caps 25 and 34 it will be seen that shot or other

weight material may be placed in the float 33 to suit the particular quality of oil which is being separated. The other end of the rocker 29 is curved upwardly and then downwardly, as is indicated generally at 35 and terminates in a ball 36 seatable on the upper end of a waste pipe 37 which extends vertically between the groups of flues 17, piercing the bottom of the casing 9 and having therein a suitable valve 38. The ball 36 opens and closes the waste pipe on the raising and lowering float 33 and allows the first formation of water, mud, and other B. S. to escape from the oil running out through the waste pipe 37, allowing the remainder to be taken out by the separators C, as will be brought out later. A smoke stack is indicated at 39 at the end of the casing 9 adjacent wall 18, and the lower end thereof is bifurcated as indicated at 40, and the flues 17, of course, extend into these bifurcated portions. A clean out waste pipe 41 pierces the wall 18 at the bottom of the casing between the groups of flues 17, and extends between the portions 40.

A valve 42 is provided in the clean out waste line 41, and may be opened for flushing out the casing 9, and general cleaning purposes. A pipe 43 leads from the end and top of the casing 9 to the chemical treating apparatus B.

Referring now particularly to the chemical treating apparatus illustrated to advantage in Figure 5, it will be seen that 44 designates a tank adapted to contain chemical which may be placed therein by removing the cap 45 from the neck 46. A glass tube 47 depends from the tank 44 into the neck 48 rising from the pipe 43. A valve seat 49 is associated with the top of the tube 47, and a needle valve 50 is mounted for controlling the seat 49 so that the chemical in the tank will drip through the glass tube 47 as the oil flows through the pipe 43 from the heating apparatus just described to the separator about to be described.

The pipe 43 leads to a gas separating mechanism which is designated generally by the letter F, and includes a plurality of vertical pipes 51, 52, 53, and 54. We have shown four of these pipes, but the number thereof may be decreased or increased depending entirely upon circumstances, and more particularly upon the size of the separator C. These pipes 51 to 54 inclusive are connected by a pipe 55 having an escape pipe 56 leading therefrom. At the point of communication of the pipe 55 with pipes 52, 53, and 54 there is provided a break gate 57, similar in construction and purpose to the break gate 23, previously described in detail. The pipes 51 to 54 inclusive all communicate with and rise from a casing 58 having a dome 59 rising therefrom between pipes 51 and 52. A cap 60 is threaded on

top of the dome so that access may be had to the float 61 which is in the form of a hollow container having a cap 62 so that the suitable weighted material may be placed therein. A standard 63 rises from the bottom of the tank 58 and a rocker 64 is pivoted intermediate its ends as at 65 to the standard 63. One end of this rocker 64 is pivoted as at 66 to the bottom of the float 61 to be actuated thereby. A waste line 67 leads through one end of the tank 58 and terminates in the tank in a downwardly disposed extension 68 having a valve seat 69 therein with which cooperates a valve 70 adjustably mounted as at 15 71 on the other end of the rocker 64, so that as the float 61 lowers, the valve 70 closes. The float 61 is weighted so that it will float in water, but sink in oil so that as the water accumulates in the bottom of the tank 58 the 20 float will rise to open the valve so that the water may flow out with the B. S. through the pipe 67. The good oil is taken off through the pipe 43 which communicates with the pipe 54 through pipe 75 at the 25 point where the break gate 57 is located.

It is thought that the construction, operation, and advantages of this invention will now be clearly understood without a more detailed description.

It is desired, however, to point out that the heating apparatus makes this separating apparatus adaptable to any climate under any circumstances, and so that the apparatus will separate any gravity or quality of oil, 30 as the application of heat, together with the forcing of the oil through the perforated feed tube 19 in the bottom of the boiler-like casing 9, and again through the perforated crown sheet 16 breaks up the globules so 35 that the very last part of the water may be separated from the oil as is desirable. The chemical treating equipment affords an efficient, reliable and convenient means for injecting the chemical into the oil when it is 40 most receptive therefor. The flood or break gate equipment 57 in the gas separating equipment F is located above the separator which is very similar in construction and the same in principle as the separator shown in 45 the application filed by us on September 4, 1925, and assigned Serial No. 54551, just breaks the oil more extensively, making it possible that the same may be separated, the gas escaping through the escape pipe 56, and 50 finally allowing the pipe line oil to pass out through the pipe 73.

The present embodiment of our invention has been disclosed in detail because in actual practice it attains the features of advantage enumerated as desirable in the statement of the invention and the above description. It will be apparent, however, that numerous changes in the details of construction, and in the combination and arrangement of parts may be resorted to without 55

departing from the spirit and scope of the invention as hereinafter claimed or sacrificing any of its advantages.

Having thus described the invention, what we claim as new is:—

1. A heating and separating unit for an apparatus of the class described including, in combination, a boiler like casing, a fire box structure associated with the casing, flues leading from the fire box through the bottom portion of the casing, a perforated feed tube in the bottom of the casing between the flues, a perforated crown sheet over the flues, a standard rising in the casing, a waste pipe extending into the casing, 75 a rocker pivoted on the standard and having a valve closable over the waste pipe, and float means for operating the rocker.

2. A heating and separating unit for an apparatus of the class described including, in combination, a boiler like casing, a fire box structure associated with the casing, flues leading from the fire box through the bottom portion of the casing, a perforated feed tube in the bottom of the casing between the flues, a perforated crown sheet over the flues, a standard rising in the casing, a waste pipe extending into the casing, 80 a rocker pivoted on the standard and having a valve closable over the waste pipe, 85 a second rocker pivoted on the standard, a link connecting the last mentioned rocker to the first rocker, a float on the second rocker in the form of a hollow container having a screw cap, a dome rising from 90 the casing and having a screw cap thereon so that access may be had to the float which is movable in the dome.

3. A heating and separating unit for an apparatus of the class described including, in combination, a boiler like casing, a fire box structure associated with the casing, flues leading from the fire box through the bottom portion of the casing, a perforated feed tube in the bottom of the casing between the flues, a perforated crown sheet over the flues, a standard rising in the casing, a waste pipe extending into the casing, 105 a rocker pivoted on the standard and having a valve closable over the waste pipe, a second rocker pivoted on the standard, a link connecting the last mentioned rocker to the first rocker, a float on the second rocker in the form of a hollow container having a screw cap, a dome rising from the 110 casing and having a screw cap thereon so that access may be had to the float which is movable in the dome, a branch leading from the perforated tube, a second branch, a second dome on the casing, said second branch 115 leading to the second dome, and valves in said branches.

4. A heating and separating unit for an apparatus of the class described including, in combination, a boiler like casing, a fire 120

- box structure associated with the casing, flues leading from the fire box through the bottom portion of the casing, a perforated feed tube in the bottom of the casing between the flues, a perforated crown sheet over the flues, a standard rising in the casing, a waste pipe extending into the casing, a rocker pivoted on the standard and having a valve closable over the waste pipe, a second rocker pivoted on the standard, a link connecting the last mentioned rocker to the first rocker, a float on the second rocker in the form of a hollow container having a screw cap, a dome rising from the casing and having a screw cap thereon so that access may be had to the float which is movable in the dome, a branch leading from the perforated tube, a second branch, a second dome on the casing, said second branch leading to the second dome, and valves in said branches, and a break gate located in the second dome at the point of communication of the second branch with said second dome.
- 23 5. A heating and separating unit for an apparatus of the class described including, in combination, a boiler like casing, a fire box structure associated with the casing, flues leading from the fire box through the bottom portion of the casing, a perforated feed tube in the bottom of the casing between the flues, a perforated crown sheet over the flues, a standard rising in the casing, a waste pipe extending into the casing, a rocker pivoted on the standard and having a valve closable over the waste pipe, a second rocker pivoted on the standard, a link connecting the last mentioned rocker to the first rocker, a float on the second rocker in the form of a hollow container having a screw cap, a dome rising from the casing and having a screw cap thereon so that access may be had to the float which is movable in the dome, a branch leading from the perforated tube, a second branch, a second dome on the casing, said second branch leading to the second dome, and valves in said branches, and a break gate located in the second dome at the point of communication of the second branch with said second dome, a gas escape pipe rising from the second dome, an oil take off pipe leading from the casing, a chemical treating apparatus associated with said take off pipe, and a gas and water separator to which said take off pipe leads.
- 24 In testimony whereof we affix our signatures.
